Primary Examiner — Charles Hanson(74) *Attorney, Agent, or Firm* — McGarry Bair PC(57) **CLAIM**

The ornamental design for a recliner chair, as shown and described.

DESCRIPTION

FIG. 1 is a front isometric view of a recliner chair which embodies a first embodiment of our design;

FIG. 2 is a rear isometric view thereof;

FIG. 3 is a front view thereof;

FIG. 4 is a rear view thereof;

FIG. 5 is a left side view thereof;

FIG. 6 is a right side view thereof;

FIG. 7 is top view thereof;

FIG. 8 is a bottom view thereof;

FIG. 9 is a front isometric view of a recliner chair which embodies a second embodiment of our design;

FIG. 10 is a rear isometric view thereof;

FIG. 11 is a front view thereof;

FIG. 12 is a rear view thereof;

FIG. 13 is a left side view thereof;

FIG. 14 is a right side view thereof;

FIG. 15 is top view thereof; and,

FIG. 16 is a bottom view thereof.

The broken line showing of the wheels is included for the purpose of illustrating unclaimed subject matter and forms no part of the claimed design.
